MECHANICAL HAND POWERED SOAP
BUBBLE MAKER

Gaither J. King, Norfolk, Va.

Application January 16, 1948, Serial No. 2,761

3 Claims. (Cl. 46—8)

1

This invention relates to mechanically actuated bubble blowing machines wherein a disc with openings therein is rotated alternately through a soapy solution and a current of air, and in particular a manually operated machine having a train of gears with a hand crank, a fan rotated by the gears, a bubble carrying disc also rotated by the gears, and means directing air from the fan through the disc.

The purpose of this invention is to provide a mechanically actuated bubble blowing machine that may be operated by hand.

Various devices have been provided for carrying films of liquid adapted to form bubbles through a current of air so that bubbles are formed from the liquid but these are provided as separate units or are comparatively complicated so that they are not adapted for universal use. With this thought in mind this invention contemplates a comparatively simple unique casing having a solution compartment with a fan and disc in combination therewith, and a crank for rotating the fan and disc through gears wherein the disc turns slow and the fan relatively fast.

The object of this invention is, therefore, to provide a unique hand operated mechanically actuated bubble making machine wherein a single crank operates a bubble disc at slow speed and a fan at comparatively high speed.

Another object of the invention is to provide a mechanically actuated bubble maker in which the parts may readily be cleaned.

A further object of the invention is to provide a mechanical bubble making machine which is of a simple and economical construction.

With these and other objects and advantages in view the invention consists of the new and novel combination, construction, and arrangement of parts as hereinafter more fully described, set forth in the claims appended hereto, and disclosed in the accompanying drawings forming part hereof, wherein:

Figure 1 is a view showing a side elevation of the mechanical bubble blowing machine.

Figure 2 is a view showing an end elevation of the machine with a part broken away.

Figure 3 is a similar view looking toward the opposite end of the machine.

Figure 4 is a plan view of the machine.

Figure 5 is a longitudinal section through the machine taken on line 5—5 of Figure 3 with the fan, gears, and gear support shown in elevation.

Figure 6 is a cross section through the discharge end of the machine taken on line 6—6 of Figure 5, showing the bubble carrying disc.

2

Figure 7 is a cross section through the machine taken on line 7—7 of Figure 5 showing the air scoop.

Figure 8 is a cross section through the machine taken on line 8—8 of Figure 5 showing the gears and fan.

Figure 9 is a detail showing a plan view of the gear train and fan with parts broken away and parts omitted.

Referring now to the drawings wherein like reference characters denote corresponding parts the bubble blowing machine of this invention includes a casing 10 having a centrally disposed horizontal shaft 11 with a fan 12 and a bubble disc 13 thereon, and a crank 14.

In the design shown the casing is in the form of a cylinder with supports 15 on the lower side, a perforated head 16 with an elongated slot 17 therein, through which the crank 14 extends, at one end, and with a solution compartment 18 in the lower end formed between an end 19 and a partition 20. The end 19 is provided with a transverse outwardly flared flange 21 which facilitates pouring solution into the compartment 18, and in the upper part of the end is an opening 22 with an arcuate flange 23 having a tapering upper edge which catches the drip from excess fluid on the bubbles and provides a drain therefor back to the compartment 18. The end plate 19 is provided with filling openings 24 and 25 and the compartment 18 is filled until the liquid flows through these openings, and in the upper part of the partition is an orifice 26 that is positioned to register with opening 27 in the bubble disc 13, as shown in Figure 7. The partition 20 is also provided with an arcuate web 28 which forms an air scoop that catches the air and directs it through the orifice 26.

The outer end of the shaft 11 is journaled in the partition 20 and the opposite end is rotatably mounted in flanges 29 and 30 of the gear support 31 which is mounted in the casing at the points 32 and 33, as shown in Figure 8. The crank 14 is mounted on the end of a jack shaft 34 which is journaled in the flange 30 and also in an intermediate flange 35, and the jack shaft 34 is provided with a gear element having a gear 36 and a pinion 37 which is fixedly mounted on the shaft. The pinion 37 meshes with a gear 38 having a hub 39 through which it is fixed on the shaft 11 by a set screw 40, and as the crank is turned the shaft 11 is rotated at comparatively slow speed so that the disc 13 on the outer end of the shaft turns at slow speed.

55 The gear 36 meshes with a pinion 41 of a gear

42 that is freely carried by the shaft 11, and the gear 42 meshes with a pinion 43 of a gear 44 that is freely mounted on the jack shaft 34. The gear 44 meshes with a pinion 45 on a sleeve 46 which forms the hub of the fan 12 and with the hub freely rotatable on the shaft 11, the fan will be rotated at comparatively high speed. The gear support is provided with a bar 47 which supports the intermediate flange 35, as shown.

With the parts arranged in this manner the compartment 18 may be filled with a soapy solution or the like, and as the crank 14 is turned the fan and disc 13 will be rotated and as the disc rotates it will pick up a film of the liquid which will cover the openings therein and the air from the fan will blow through the openings forming the film into bubbles which will float from the machine.

It will be understood that any suitable solution may be used and also that modifications may be made in the design and arrangement of the parts without departing from the spirit of the invention.

What is claimed is:

1. A bubble blowing machine comprising a cylindrical casing having a solution compartment in one end, a longitudinally disposed centrally positioned shaft journaled in the casing, a disc having openings spaced from the periphery mounted on the shaft and positioned in the said solution compartment whereby the peripheral edge thereof passes through the lower part of the compartment as the disc rotates with the shaft, a sleeve rotatably mounted on said shaft, a fan in the intermediate part of the casing carried by the sleeve and positioned to blow air through the openings of the disc and through the upper part of the solution compartment, and means rotating the fan and disc with the speed of the fan being greater than that of the disc.

2. A bubble blowing machine comprising a cylindrical casing having a solution compartment in one end, a longitudinally disposed centrally positioned shaft journaled in the casing, a disc having openings spaced from the periphery mounted on the shaft and positioned in the said solution compartment whereby the peripheral edge thereof passes through the lower part of the compartment as the disc rotates with the shaft, a sleeve rotatably mounted on said shaft, a fan

in the intermediate part of the casing carried by the sleeve and positioned to blow air through the opening of the disc and through the upper part of the solution compartment, a gear train positioned in the casing and rotatably connecting the sleeve to the shaft, and a hand crank extended from the casing for rotating the shaft and disc through the gear train.

3. In a mechanically actuated bubble blowing machine, the combination which comprises a cylindrical casing having a transverse partition spaced from one end providing a solution compartment between the partition and end of the casing, the opposite end of said casing being perforated and the said partition and end of the casing from which the partition is spaced having aligned openings therethrough, a longitudinally disposed shaft journaled in the casing, a disc having openings spaced from the periphery mounted on the shaft and positioned in the said solution compartment whereby the peripheral edge thereof passes through the lower part of the compartment as the disc rotates with the shaft said openings of the partition and end of the casing being in register with the opening through the disc, a jack shaft also journaled in the casing and spaced from the longitudinally disposed shaft, a sleeve on the longitudinally disposed shaft having a fan on one end thereof, a train of speed changing gears mounted on the jack shaft, the longitudinally disposed shaft and sleeve, and a hand crank extended from the end of the jack shaft for rotating the longitudinally disposed shaft with the disc carried thereon and the sleeve with the fan carried thereon with the fan rotating at a speed greater than that of the disc, said fan positioned to blow air through the openings through the partition, disc and end of the casing.
